DESIGN FOR A STEERING WHEEL

Charles W. Leck, Bloomfield, N. J.

Application July 19, 1933. Serial No. 48,758

Term of patent 3½ years

To all whom it may concern:

Be it known that I, CHARLES W. LECK, a citizen of the United States, residing at #71 Laurel Ave., in the town of Bloomfield, county of Essex, State of New Jersey, have invented a new, original, and ornamental Design for Steering Wheels, of which the following is a specification, reference being had to the accompanying drawing, forming part thereof.

Fig. 1 is a plan view of a steering wheel showing my new design; and

Fig. 2 is a side elevational view thereof.

I claim:

The ornamental design for a steering wheel as shown.

CHARLES W. LECK.
